(57) **CLAIM**

The ornamental design for a peg hook, as shown.

DESCRIPTION

FIG. 1 is a perspective view of the peg hook of the invention.

FIG. 2 is a front view of the peg hook.

FIG. 3 is a top view of the peg hook.

FIG. 4 is a right side view of the peg hook.

FIG. 5 is a rear view of the peg hook; and,

FIG. 6 is a bottom view of the peg hook.

The article is a peg hook adapted to be secured to a vertical surface and having two upstanding hooks.
